CARBURETOR

George M. Holley, Grosse Pointe Farms, Mich.

Application January 28, 1936, Serial No. 61,247

4 Claims. (Cl. 261—72)

The object of this invention is to provide means whereby a self-lift carburetor will automatically increase the lift on its fuel supply chamber when a car is climbing a hill and during the early stages of accelerating from a low engine speed. When a tank is located in the rear and the engine in front, the lift required increases from 22 inches to almost 50 inches on a 25% grade. Obviously, if the carburetor is designed to perform on the level, the air flow should be the greatest possible and therefore the resistance of the air valve will be as little as possible. Hence the resistance created by the air valve should be just sufficient to lift the fuel 22 inches when idling. When climbing a hill such an air valve will not create sufficient lift to raise the fuel to the float chamber of the car. I have discovered that if I hang a weight on the air valve less than 40°, for example 20° from the vertical and arrange that this weight swings out into the direction of motion of the vehicle so that when the air valve is wide open, this weight is over 70° and less than 90° to the vertical, then on ascending a hill the effective torque of the weight when idle will be increased 50 or 90% depending on the steepness of the hill, whereas the effective torque when the air valve is wide open would only vary 1 1/2%. Effective pounds inch torque of one pound at a radius of 1" when the valve is inclined from the vertical on a hill is as follows:

90% increase in lift when idling on a hill is desirable.

By arranging that the weight swings from about 20° to 30° when idling and from 80° to 90° wide open, I can obtain the desired result, namely, an air valve which automatically increases the lift when idling on a hill and does not change the resistance to air flow appreciably when an engine is running at high engine speed on a hill. The power of the engine at top speed is thus not interfered with but the performance at part throttle and low engine speed is greatly improved. During acceleration from 7 M. P. H. at say 3 or 4 feet per second, obviously there is a greater demand for fuel and to this demand the weighted air valve responds. As the car gains speed the weight assumes its horizontal position and the effect of acceleration disappears automatically.

Figure 1 shows diagrammatically the carburetor in the position it assumes when climbing an extremely steep hill.

Figure 2 shows the corresponding parts with the air valve substantially wide open.

In the figures, an air valve 11 is counterbalanced by a weight 12, the center of gravity of which is at A. The center of the air valve 11 is at B. A vertical ordinate B—C dropped from the center B and a corresponding ordinate A—D dropped from the center of gravity A indicate that the weight 12 has a leverage C—D around the center B. When the carburetor is horizontal, that is, when the plane E—F is horizontal, the vertical ordinate B—G dropped from the center B and the vertical ordinate A—H dropped from the center of gravity A perpendicular to the plane E—F demonstrates that the leverage of the weight 12 around the center B is equal to G—H.

If J—K indicates the horizontal plane when climbing a hill indicated by the plane E—F, then the effect of going from the horizontal plane J—K to the inclined plane E—F will be to increase the leverage of the weight 12 around the center B from the leverage G—H to the leverage C—D. It will be noted that this is due to the fact that the angle B—A makes with the line B—G is small. When this angle increases, that is, when the air valve 11 opens, the effect of going from the horizontal plane J—K to the hill indicated by the plane E—F will be negligible. In other words, when the line B—A is substantially horizontal, the leverage of the weight 12 resisting the opening of the air valve 11 will not vary appreciably with the inclination of the hill.

13 is the air entrance. 14 is the cylindrical

	Idle		Wide open		Hill	
	Valve angle	Torque	Valve angle	Torque	Degrees	Percent grade
35	°	Inch pound	°	Inch pound		
	20	0.34	80	0.985	0	Level
	30	0.50	90	1.00	10	17 1/2
40	40	0.64	100	0.985	20	34

The carburetor when running at high speed creates sufficient vacuum on the fuel nozzle due to the high air velocity so that the fuel nozzle has no difficulty in taking the fuel away from the float chamber even though the float chamber has in it a vacuum of 50" of gasoline. Hence, it is possible to maintain at all times sufficient vacuum in the float chamber to climb any hill at high engine speed. The difficulty comes when it is required to idle the engine on a hill or to climb the hill with the engine running at low engine speed, wide open. In either event, there is a shortage of lift and this is especially noticeable when idling on a hill. Hence, a 50 to

housing in which the air valve 11 rotates. 15 is the space back of this housing in which the weight 12 moves. It is noted that this space is under the depression below the air valve 11. 16 5 is the stop in the air entrance 13 against which the air valve 11 comes to rest when the engine is not running. 17 is the entrance to the air bypass around the air valve 11. The air drawn through this bypass passes through the small venturi 18 and discharges through the tube 19. 10 This tube 19 terminates in the throat 20 of the main air passage. Located in this throat 20 is the throttle 21. The tube 19 terminates adjacent to this throttle as shown in my co-pending 15 patent Serial No. 744,160. The throat 20 discharges into the mixture outlet 45 with which it forms a Venturi passage.

Fuel is supplied from a tank, not shown, to a pipe 22 through the float valve 23 controlled by 20 the float 24. Float valve 24 is contained in a float chamber 25, the upper part of which 26 communicates through a pipe 27 with the throat of the venturi 28. A second air bypass 29 supplies air from the air entrance 13 to this venturi 28 and to the passage 30 which communicates through the restriction 31 to the underside of the air valve 11, the area of which restriction 31 is controlled by a needle valve 32 which is connected by means of a link 33 with the air 25 valve 11.

It will be noted that the air flowing through the passages 29, 28, 30, and 31 discharge into the space 15 in which the weight 12 swings, that is, on the vacuum side of the air valve 11. The 35 air valve thus controls the depression in the upper part 26 of the float chamber 25. The flow of fuel from the float chamber 25 to the small venturi 18 is controlled by the throttle in the following manner. A throttle lever 34 controls 40 the movement of the throttle 21. A lever 35 is connected through a link 36 with a rocking lever 37 which is connected through a link 38 with a hook 39, which carries the needle valve or economizer pin 40. This economizer pin is 45 guided in tube 41 and controls the fuel flow.

through a restriction 42 which is connected by a passage 43 with the orifices 44 located in the down stream side of the throat of the small venturi 18.

Figure 2 shows the position the weight 12 assumes when the air valve 11 is wide open. 5

What I claim is:

1. A fuel lift carburetor for motor vehicles having an air entrance, an automatic valve therein, a mixing chamber, a mixture outlet 10 therefrom, a throttle valve therein, a fuel supply chamber, a fuel passage leading therefrom discharging into the throat of a Venturi passage through which air is bypassed into said mixing chamber around said air valve, a second Venturi 15 passage through which air is also bypassed around said air valve into said mixing chamber, a passage connecting the throat of said second venturi with the upper part of said fuel supply chamber so as to create a vacuum therein, means 20 for increasing this vacuum when a vehicle is ascending a hill, comprising a weight attached to said air valve and adapted to swing as the air valve opens into the direction of motion of the vehicle. 25

2. In a fuel lift carburetor as described in claim 1 in which the plane passing through the axis of the swinging weight and its center of gravity is substantially horizontal when the air valve is wide open and the vehicle is moving in 30 the horizontal plane.

3. A fuel lift carburetor as described in claim 1 in which the plane passing through the axis of the swinging weight and its center of gravity is less than 40° to the vertical when the air valve 35 is in its closed position and the vehicle is on a horizontal plane.

4. A fuel lift carburetor as described in claim 1, in which the center of gravity of the swinging weight oscillates in a substantially vertical plane 40 parallel to the direction of motion of the vehicle from a position of less than 40° to the vertical when the air valve is closed to one of over 70° when the air valve is wide open.
